[57] CLAIM

The ornamental design for a vehicle remote keyless entry transmitter, as shown and described.

DESCRIPTION

FIG. 1 is a front perspective view illustrating a vehicle remote keyless entry transmitter constructed in accordance with the teachings of the present invention, it being understood that the hidden line showing of the key rings is for illustrative purposes only and forms no part of the subject invention;

FIG. 2 is a top view thereof;

FIG. 3 is a bottom view, thereof;

FIG. 4 is a front view thereof;

FIG. 5 is a rear view thereof;

FIG. 6 is a right side view thereof, it being understood that the side opposite to that shown is a substantial mirror image thereof.
